INVENTOR.
Walter Tabert,

Geo. Kimmel

ATTORNEY.

UNITED STATES PATENT OFFICE.

WALTER TABERT, OF EAST GRAND FORKS, MINNESOTA.

WRENCH.

Application filed August 6, 1923. Serial No. 655,974.

To all whom it may concern:

Be it known that I, WALTER TABERT, a citizen of the United States, residing at East Grand Forks, in the county of Polk and State of Minnesota, have invented certain new and useful Improvements in Wrenches, of which the following is a specification.

This invention relates to wrenches of the sliding jaw type, and has for its object to provide a wrench of such class, in a manner as hereinafter set forth, with means to permit of the convenient adjustment of the sliding jaw with respect to the work, as well as further including means for clamping the sliding jaw to the work when the wrench is manipulated for the purpose of removing or securing the work from or in position.

20 A further object of the invention is to provide a wrench of such class, in a manner as hereinafter set forth, including means for adjusting the sliding jaw with respect to the work, as well as locking the jaw in its adjusted position, and further with means, if any looseness is present between the jaws of the wrench and the work, whereby the sliding jaws and its locking means will be bodily shifted to securely clamp the work 30 when the wrench is manipulated to remove the work from or secure it in position.

Further objects of the invention are to provide a wrench of the adjustable sliding jaw type, in a manner as hereinafter set forth, and which is simple in its construction and arrangement, strong, compact, thoroughly efficient in its use, including means to provide for the convenient adjusting of the sliding jaw as well as means for conveniently clamping the sliding jaw against the work, and inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference

characters denote corresponding parts throughout the several views:—

55 Figure 1 is a side elevation of a wrench in accordance with this invention.

Figure 2 is a sectional elevation.

Figure 3 is a section on line 3—3, Figure 2.

60 Figure 4 is a section on line 4—4, Figure 2.

Figure 5 is a fragmentary view of the intermediate portion of the wrench looking towards the front thereof.

65 Referring to the drawings in detail, a wrench in accordance with this invention consists of a body portion 1 having a bifurcated inner portion 2 and a stationary jaw 3 formed integral with the outer end 70 thereof. The body portion 1 is formed with a lengthwise extending chamber 5, having the rear wall 6 thereof closed and the front wall 7 provided with a lengthwise slot 8 which is of materially less width than 75 the width of the rear wall 6 and is disposed centrally with respect thereto. The setting up of the front wall 7 with the slot 8 provides a pair of oppositely extending shoulders 9. The slot 8 extends from the jaw 3 to 80 the bifurcated inner end of the body portion 1. The shoulders 9 constitute what may be termed combined seats and guides for the carrier, to be presently referred to, 85 of the slidable jaw.

The outer end wall of the chamber 5 is provided by the inner face of the stationary jaw 3 and said outer end wall is formed with a pocket 10 and a socket 11. Arranged in the socket 11, as well as projecting therefrom, is a coiled spring 12, having its rear end connected to a toothed stop bar 13 which slides against the inner face of the wall 6. The teeth of the bar 13 are indicated at 14 and are of the ratchet type. 90 The rear end of the bar 13 is formed integral with a plate 15 which rides against the walls 6 and 7 and extends into the bifurcated inner portion of the body portion 1, and has the rear end thereof bevelled, as 95 16. The plate 15 also rides against the side walls 17 and 18 of the chamber 5 and extends across the inner end of the slot 8.

100 Arranged within the chamber 5, is a carrier 19 provided at one end with an extension 105 20 adapted to engage in the pocket 10 when

the carrier is shifted towards the jaw 3, and said extension constitutes means for spacing the sliding jaw 21 from the jaw 3 when the sliding jaw 21 is shifted to the limit 5 of its adjustment towards and with respect to the jaw 3.

The carrier 19 has an outer reduced portion 22 which slides against the walls of the slot 8 and the rear part of the reduced portion 22, as indicated at 23, projects forwardly from the slot 8 and is formed with a pair of apertured ears 24, as well as with an opening 25. Formed integral with the wider part, as well as with the smaller part 15 of the reduced portion 22, is the sliding jaw 21 and the latter is adjusted relative to the jaw 3, when the carrier is shifted within the chamber 5.

The carrier 19, below the extension 20, is 20 formed with an enlarged rectangular recess 26, in which is arranged a spring controlled toothed locking member 27 which engages with the teeth 14 to arrest rearward shifting of the carrier when the latter has been adjusted 25 and when the member 27 is in engagement with the bar 13. The bottom of the recess 26 and which is indicated at 28, is provided with a pair of pockets 29, which oppose a pair of pockets 30 formed in the member 27, and arranged in the opposed pockets are 30 coiled springs 31 which are provided to normally maintain the member 27 projected from the carrier to engage the bar 13.

The locking member 27 is retracted into 35 the recess 26 for the purpose of releasing the carrier 19 from the bar 13, by a pull rod 32, which has its inner end fixed to the member 27 and which further extends through the opening 25 and has a hook-shaped outer end 33. Mounted on a pivot pin 34 carried by the ears 24, is a shifting lever 35 for the pull rod 32, and said lever 35 has an apertured forward end 36 for the reception of the hooked end 33 of the rod 32, whereby the latter and lever are loosely connected together and furthermore by connecting the rod 32 with the lever 35 in the manner as stated, when the upper end of the lever 35 is moved away from the carrier 40 19, the rod 32 will be carried therewith, under such conditions retracting the member 27 into the recess 26, causing thereby the release of the carrier from the bar 13 and allowing of the jaw 21 to be adjusted in 45 the desired position with respect to the jaw 3.

The inner or larger part of the carrier 19 slides against the combined seats and guides formed by the inner face of the wall 60 7 and that part of the carrier which projects forwardly of the slot 8 is of a width to slide against the outer face of the wall 7, as indicated at 37 in Figure 4. The width 65 of the jaw 21 is such that it will slide against the outer face of the wall 7, or in

other words, the length of the part of the carrier which projects from the slot 8 is the same as the width of the jaw 21.

The reference character 38 denotes a handle member which has a reduced end 39 70 extending between the bifurcated inner end 2 of the body portion. The reduced end 39 is pivotally connected to the inner end of the body portion 1 by the pin 40 and said end 39 has an inclined edge 41 which opposes the bevelled edge 16 of the plate 15 when the handle 38 is in normal position and said reduced end 39 has a cam surface 42, so that when the handle 38 is swung in one direction the bar 13 will be moved towards 80 the jaw 3, whereby the carrier 19 and jaw 21 will be carried therewith so that the jaw 21 will clamp the work. The reduced end 39 is furthermore provided with an extension 32 which opposes the rear edge of the 85 plate 15 when the handle 38 is in normal position as shown in Figure 2.

From the foregoing construction of wrench, it not only provides for the adjusting of the sliding jaw 21 with respect to the 90 work, as well as locking said jaw 21 from rearward shifting after it has been adjusted, but the wrench further includes means, if any looseness is present between the work and the jaws 3 and 21, whereby the jaw 21 will be shifted to tightly clamp the work during the manipulation of the wrench, due to the swinging of the handle 38 on the pivot 40 so that the cam surface 42 will engage the plate 15 and shift not only the 100 bar 13 but the carrier, locking member and jaw 21 bodily so that the work will be tightly clamped between the jaws 3 and 21, and although the preferred embodiment 95 of the invention is as illustrated and described, yet changes in the details of construction can be had which will fall within 105 the light of the invention as claimed.

What I claim is:—

1. A wrench comprising a body portion 110 provided at one side with a lengthwise extending slot, a chamber and a laterally extending stationary jaw, a spring controlled toothed bar arranged within said chamber, an adjustable carrier slidably mounted 115 within said chamber and having a reduced portion extending through said slot, a shiftable jaw formed integral with said reduced portion and opposing the stationary jaw, a 120 spring controlled locking member mounted in the carrier and engageable in the bar for maintaining the carrier in its adjusted position, pivoted means connected with the carrier for shifting said locking member to released position with respect to said bar, and a handle extending into the rear end of and pivoted to said body portion and provided with a cam surface for shifting said bar whereby said carrier will be moved 125 towards said stationary jaw. 130

2. A wrench comprising a body portion provided with a chamber and a stationary jaw, a spring controlled toothed bar arranged within said chamber, an adjustable carrier slidably mounted within and projecting from said chamber, a jaw integral with the carrier and opposing the stationary jaw, a spring controlled locking member bodily movable with the carrier and engageable in said bar for maintaining the carrier in adjusted position, means for shifting said locking member relative to the carrier from engagement with said bar, and means for shifting said bar whereby said carrier and locking member will move towards said stationary jaw. 15
